UNITED STATES PATENT OFFICE.

FRANCIS J. WALLACE, OF WASHINGTON, DISTRICT OF COLUMBIA, ASSIGNOR TO
WARREN-WALLACE SYNDICATE, OF WASHINGTON, DISTRICT OF COLUMBIA,
A CORPORATION OF THE DISTRICT OF COLUMBIA.

REGULATING DEVICE FOR INTERNAL-COMBUSTION ENGINES.

1,326,381.

Specification of Letters Patent. Patented Dec. 30, 1919.

Application filed October 11, 1919. Serial No. 330,021.

To all whom it may concern:

Be it known that I, FRANCIS J. WALLACE, a citizen of the United States, residing at 309 McLachlan Bldg., Washington, in the 5 District of Columbia, have invented certain new and useful Improvements in Regulating Devices for Internal-Combustion Engines; and I do hereby declare the following to be a full, clear, and exact description of the invention, such as will enable others skilled in the art to which it appertains to make and use the same.

My invention relates, broadly, to regulating devices for internal combustion engines; 15 and, especially, to an apparatus for controlling the supply of vapor and air, creating a motor-brake by air supplied to the engine, rendering the mixture in the engine incom- 20 bustible by supply of excess air, setting an alarm to be operated by the engine when it is intended that the engine shall not operate, and cutting out the ignition devices.

I propose to control the distribution of the vapor and air, the creation of a motor-brake, 25 the destruction of the combustible quality of the mixture supplied to the engine, to provide an alarm which shall be operated upon any attempt to start the engine when it is intended that the engine shall not operate, 30 and ignition controlling devices, all in a single compact device which may be applied between the dash board and instrument board, and shall be governed by a direct acting single means.

35 I accomplish these and other objects by a ported cylinder controlled by a piston-valve through a hand-operated stem having devices which will enable me to secure what may be termed a positive micrometer control.

40 By these means I admit vapor to the intake manifold to enrich the gas coming from the carburetor, admit air to lean the mixture going to the engine, admit great quantities of air to so dilute the mixture as to render it 45 incombustible and to serve as a motor-brake in the engine; and by the same means I set for warning against any unauthorized attempt to use the car, siren whistles, short circuit the magneto and break the circuit to 50 the battery preventing at the same time both combustion and ignition.

My device is applied upon an automobile with a pipe connection leading from the

radiator to the cylinder of my device and with a pipe connection leading from the cylinder to the manifold. When the piston is pushed in to the engine or discharge end of the cylinder of my device the ports admitting vapor and atmospheric air are closed. 55 By a slight operation, a rotation, of the handle of the stem connection with the hollow piston-valve the vapor port is partly opened. By a still further movement away from the discharge end of the cylinder the vapor port is completely uncovered and the 60 atmospheric air ports are partially opened permitting the combined vapor and atmospheric air to join the gas entering the engine. By a third movement of the piston-valve away from the discharge end, the atmospheric air ports are still further opened, 65 permitting the entrance of such quantities of atmospheric air as to create a motor brake in the engine while running down hill, for example, and also destroying the combustible 70 quality of the mixture, thus serving as a lock to the motor by preventing a propelling operation. Upon a fourth and final move- 75 ment of the piston-valve, whistles are made operative to serve as a warning in case of an attempt by an unauthorized person to start the engine, and at the same time the device cuts out the ignition circuits through the operation of pins carried by the whistles.

Figure 1 is a diagrammatic view illustrating my invention applied to an automobile and indicating the arrangement of the parts of my device with respect to the radiator, engine, etc.

Fig. 2 is a plan view with the motor locked 80 and whistles closed ready for alarm in case of an unauthorized attempt to start the motor by crank or starter;

Fig. 3 is a side view of the devices shown in Fig. 2;

Fig. 4 represents the opposite position to that of Fig. 2, the whistles inoperative, the ported piston at the discharge end of the cylinder covering the atmospheric ports of the cylinder, a position held when the engine 100 is to be started;

Fig. 5 shows the first operating position, the stem of the ported piston turned with the communication to the vapor partly open;

Fig. 6 shows the device in the second position with the air and vapor supply open,

and with the atmospheric supply open so that the mixture is leaned to a degree desirable when running the engine under ordinary conditions of load, road and weather;

5 Fig. 7 shows the stem turned to the third position with the ported piston drawn farther back and further opening the atmospheric ports and permitting the cams of the whistles to begin to pass through the atmospheric ports of the cylinder and piston valve.

10 The atmospheric ports are now permitting great quantities of air to enter the engine so that the air will operate as a motor brake, 15 the engine pistons reciprocating by the action of the car in running down-hill, and having to compress the air in the engine cylinder. This figure also illustrates the position in which the quantity of air entering 20 the engine will destroy combustion and "lock" the car, that is, prevent its being started by the ignition device.

25 The supply of vapor is automatically cut off when the engine stops firing by a vapor trap to prevent the admission of moisture in such case.

30 Fig. 8 shows the final position of the parts with the piston-valve farther removed from the discharge end of the cylinder and the 35 whistles drawn against the sides of the cylinder and in communication therewith. In this position also a contact pin carried by a whistle is brought against the magneto pins to ground the circuit and the contact pin is moved out of the battery circuit to break it, thus cutting out the ignition devices.

40 While in this position any attempt to operate the engine will result in a suction through the cylinder of my device created by the intake stroke of the engine piston, and by this suction air will be drawn through the whistles sounding an alarm as long as there is any operation of the engine.

45 Fig. 9 is a section on the line 9—9 of Fig. 8 to show the details of the whistle connections;

50 Fig. 10 is a detail showing the manner in which the valve stem is readily controlled and its different movements indicated;

55 Fig. 11 is a section of the trap shown in Fig. 1 as located upon the head of the radiator.

Fig. 1 also shows the lock applied to the stem; and Figs. 2 and 3 the relation between the circuits and the contact pins carried by the whistles.

60 Figs. 2 and 3, as before stated, show my device in the position when the car is not in use, Fig. 1 further showing the application of the lock or padlock over the threaded part of the stem shown in Figs. 2 and 3. In that position the whistles are drawn closely against the cylinder of my device so that there is no air inlet between the cylinder and the body of the whistles, and any

air entering must be drawn in through the whistles by the engine.

It may be observed here that the lock must be taken off before the device can be operated and that the mere fact of the driver having the lock on his person indicates at once that the device has not been locked to prevent unauthorized use.

75 In the drawings, 20 represents a radiator with the customary water head 21. 22 is a customary water feed pipe leading to the circulating system of the engine 23. 24 represents a manifold intake, and 25 the end of the feed pipe leading from the carburetor. 26 is an air and vapor feeding tube connecting the cylinder of my device and the manifold. 27 is a pipe leading from my device to a trap 28 attached to and communicating with the water head 21 of the radiator.

80 29 is the main body or cylinder of my device which is attached between the customary dash-board and, an instrument head 30 by means of a flange or plate 31.

85 32 is a threaded opening on the discharge end of the main body or cylinder of my device, to which is secured, as indicated, an end of the feed pipe 26. 33 indicates the port to which vapor is fed from the radiator through the pipe 27. 34 indicates atmospheric ports, 90 one on each side, leading into the cylinder 95 29.

100 It will thus be apparent that there are two ports 33 and 34 leading into the cylinder and a discharge opening 32 through which the vapor or its mixture with atmospheric air may pass to the intake manifold there to be mixed with the gas being introduced from the carburetor, or to be supplied in such quantities as to form a motor brake when the car is running down-hill, for example; and a "lock" when the engine is at rest by rendering the mixture incombustible so that the air, vapor and gas may be simply an inoperative mixture incapable of starting the motor.

110 Within the cylinder there is a hollow piston-valve 35 with ports 36 on opposite sides and a slot 37 taking over a pin 38 having a screw head to hold the piston-valve centrally and in register with the atmospheric air ports 34. The piston-valve is so arranged that it may cover all the ports admitting air to the chamber, may then partially or entirely uncover the vapor port, and, finally, 115 still further or entirely uncover the atmospheric ports.

120 In Fig. 4 perforations are shown in the end of the piston-valve. The piston, therefore, is a balanced piston so that it may operate uniformly under any condition of suction in varying machines.

125 A stem 39 is secured to the head of the hollow piston which operates through a head guide 40 when the stem is drawn back and forth. The stem 39 is reduced at the lower 130

end at 41 and passes through a collar 42 on the head of the hollow piston, being secured by a button or disk on the bottom of the stem. This provision enables the stem to be turned freely in the head of the hollow piston and to operate the piston in longitudinal directions.

It will be observed that by this positive micrometer control I have provided for the 10 finest adjustments.

On the side of the stem is a key 44 adapted to take into a slot 45 in the guide 40. The stem has a hand-wheel or control knob 46 for convenient operation, and on the 15 hand-wheel is a mark of some character, as, for example, that illustrated at 47. This mark is arranged in line with the key 44. The operator knows this and being advised of the exact turn required may bring the 20 key into register with the slot 45 so that the piston-valve may be drawn to its extreme position against the head guide 40, the key 44 entering the slot 45.

48 designates a threaded projection (see 25 Fig. 10) on the flange or head 31 having a recess 49 on the bottom. In the threaded projection operates a screw 50 with a circular enlargement at the bottom operating against a spring 51 to control the pressure 30 of an anti-friction ball 52 running in spiral grooves or threads 53 on the stem 39, so that the turning of the stem may be easy and yet regulated.

In this device the ball 52 will prevent a 35 too easy rotation of the stem and at the same time will operate as an anti-friction ball to prevent an undue stiffness in the rotation of the stem 39. I have provided for an exact relation between the needs of the engine for 40 vapor and air and the size of the ports and their regulation. In running the engine, I secure a precise adjustment by the arrangement of the stem and the piston-valve while at the same time I can, to meet an emergency, draw out the valve to open the atmospheric ports to create a motor-brake; and before starting I can quickly push in the piston-valve, the stem 39 in this case reciprocating, the ball 52 being pushed up as the 45 threaded stem forces its way through the guide 40. In drawing back the knob 47 in an emergency the piston-valve first brings up with the stop 44 against the bottom of the head 40, but a slight turn of the stem 50 to bring the stop into alignment with the slot 45 will permit the complete outward movement of the piston-valve.

In Fig. 10 I have illustrated an adjunctive detail. 520 represents a notch at one 60 side of occasional turns of the groove in the threaded portion of the stem 39. These notches correspond with the conclusion of the separate stages in the turning of the knob 36 and the stem 39, so that the ball 52 65 at either stage will drop into the notch in its

passage about the groove thus giving a sharp click to indicate to the driver that he has made the desired turn of the control knob. These notches 520 are shown in the second and fourth turn, the next turn being indicated to the driver by the stop 44 coming against the bottom of the head 40.

A small rotation or reciprocation of the stem 39 of the piston-valve 35 secures the desired result. I may set the screw 50 controlling the pressure of the ball 52 so that the device may be easily adjusted for all kinds of cars and yet so that the stem 39 may be pushed and drawn out rapidly against the resistance of the spring-pressed ball, as before indicated.

The sound indicating provision is especially useful for night driving. It may also be observed that in time the position that the stem 39 or the control knob 46 assumes 85 will become a sufficient guide to one familiar with my device.

The vapor trap, 28, shown in detail in Fig. 11 is divided by a central seat 54 into two chambers 55 and 56. The valve seat is 90 perforated, as illustrated at 57, two of the perforations there being illustrated, it being understood that there may be any number. 58 represents a valve controlling the perforations and having about its stem a 95 spring 59 bearing at the other end against a disk 60 governing the opening to the air in the bottom chamber. 61 is a pipe leading into the water chamber of the radiator. When the vapor port 33 is open to the cylinder 100 29 the vapor passes up through the perforations and through the feed pipe 27. When the port 33 is closed, the valve 58 seats to close the perforations 57, and opens the bottom chamber to the air by the consequent lowering of the disk 60, thus permitting the escape of condensed moisture.

62 represents opposing ears on the cylinder, 63 arms on each whistle body embracing the perforated ears on the cylinder body 110 and 64 pins which pass through the arms and ears so that the bodies of the whistles, 65 and 66, are swiveled, being drawn together when permitted by a spring 67. Each whistle bears a cam 68 adapted to enter the opposite atmospheric port 34 when the hollow piston is drawn back uncovering it. Thus, when the atmospheric ports are open 115 the cams 68 will begin to slide off the walls of the piston-valve, as shown in Fig. 7, and 120 will finally completely enter the cylinder when the piston is drawn back to the position shown in Fig. 8, permitting the spring 67 to bring the properly formed walls of the whistle bodies tightly against the cylinder body registering the whistle with the air ports of the cylinder. The whistle is composed of a many ported disk 69 over 125 which turns a ported revolving disk 70 centered and secured to a rotor pin 71 with 130

pointed end resting against the bottom of a screw 72 passing through a ported rib 73. In short, an ordinary "siren whistle". It will be observed that the whole of the whistle 5 cylinder may be slipped into place easily and secured in a threaded enlargement at the end of each whistle body.

74 and 75 represent extending ears on the whistle body through which pass pins 76 10 and 77 with a spring 78 engaging each pin near the bottom and pressing against the upper ear so that the pins may play in the ears. The pins are preferably arranged as yielding contact pins pointed at the lower 15 end so that they may slide over the insulated bar 79 and contact with the ignition controlling circuits.

In my device I have shown the two circuits, the one on the right, 80 in Fig. 2, for 20 example, being the magneto circuit, and the other one on the left, 800, the battery circuit. In the operation of my device when the whistles are drawn close against the cylinder the pins 76 and 77 are brought over 25 the board 79 so that the pin 76 closes the magneto circuit at 80 grounding it through the apparatus. At the same time the pin 77 is taken away from the battery circuit 800 breaking the circuit, which is closed 30 when the whistles are again forced away from the cylinder into the positions shown, for example, in Fig. 7.

By this means it will be observed that I do away with the customary switches and 35 substitute for them in this compact arrangement of parts the pins 76 and 77 carried by a part of the apparatus which is intended to be brought into operation at the time necessary to break the battery circuit and 40 similarly dispose of the magneto circuit, in this case by grounding the circuit.

530, as shown in Figs. 1 and 8 and indicated in Fig. 2, represents a lock which can not be applied until the final movement 45 away from the cylinder is had because it is of a form to just fit between the cone base of the control knob 46 and the extension of the guide 40 receiving the threaded section 53 of the stem. This provision serves to 50 mind the driver that the whistles are not set until the control knob is in the final position with the piston-valve fitting up against the bottom of the stem guide 40.

The pushing in of the stem 39 carries the 55 piston-valve 35 down against the whistle-cams 68, pushing them out, destroying the closure between the whistles and the cylinder 29 and closing all the ports. Having reached that position shown in Fig. 5 the 60 driver draws up the piston-valve admitting vapor to the cylinder 29 through the inlet 33. Another or second turn, as in Fig. 6, draws up the piston-valve partially opening the ports 34 admitting atmospheric air 65 to be combined with the vapor entering the

cylinder through the port 33 so that when, running ordinarily, sufficient air may be admitted to render the combustion mixture lean, thus, in accordance with known principles, saving the gas, giving more power 70 and rendering the engine more efficient. If now another and third turn be given the stem, the piston, as shown in Fig. 7, will open far enough to permit the whistle cams to start inward through the ports in the 75 piston-valve, the piston-valve still further uncovering the ports 34 to admit such quantities of air as to operate as a motor brake, the pistons of the engine operating against such quantities of air and gas as to retard 80 the engine, an operation known to be especially effective when running down hill. This manner of running down-hill, dangerous in ordinary cases, is rendered entirely 85 safe by my device.

When the fourth or final turn of the stem is given the parts will be in the position shown in Fig. 8 as before stated. The whistles have closed against the cylinder 29, the ports 34 are now entirely uncovered and atmospheric air is continuing, as in Fig. 7, to enter in such quantities as to render impossible in any event the combustion of the fluids entering the engine cylinder. Furthermore, at this time the magneto is not in 90 service, grounding having been accomplished by the moving of the pin 76 on the whistle-bodies into contact with the magneto pins, and at the same time the battery circuit 800 is broken by moving to 95 one side the pin 77 of this circuit.

Fig. 8, in fact, is Figs. 1 and 2 partially in section, but with the lock applied over the stem. When the lock is removed the stem and the connected piston-valve may be 100 at once pushed in to the position shown in Fig. 4 ready for the starting of the engine.

When the motor brake is applied in running down hill it is ordinarily inadvisable to also apply the whistles though if desired they could be applied to operate as ordinary service whistles. To prevent the operation of the whistles while at the same time getting the full supply of air to operate as a motor brake and to cut off the ignition, I 110 have provided the key 44 on the piston-valve 35 which, in this position of the parts, abuts the head 40 as shown in Fig. 7. When it is desired to have the whistles come into position close against the walls of the cylinder 29 to operate in case of an unauthorized attempt to start the car, a turn of the control knob approximately 45° to the left, brings the mark 47 in line with the slot 45 and permits the piston-valve to be drawn 115 out farther and finally fit snugly against the bottom of the guide head 40, completely opening the ports 34 and permitting the whistle-cams 68 to enter the ports 34 and the spring 67 to bring the whistle-bodies up into 120 125 130

close and practically air-tight connection with the body of the cylinder 29, the position necessary for their operation as sirens.

It will be observed that in this regulating device I provide simply by different movements, first, for admitting moisture from the radiator of the automobile to the intake manifold when the motor is in operation in quantities to suit the exact conditions of 10 weather or load, and when the motor stops firing I immediately check the vapor flow should the control remain open in the main body of my device by the vapor trap set in the connection between the radiator and 15 my device, thus preventing the admission of moisture into the engine while idle. I also provide for admitting extra atmospheric air so that if the supply coming from the carburetor should be rich enough it may 20 absorb extra air thus effecting a saving of fuel and at the same time increasing the engine speed under light loads. Again, by a slight turn of the control knob to a designated point large quantities of air may be 25 drawn into the engine with the throttle closed while running down hill thereby setting up a greater resistance in the motor and checking the momentum of the car without the danger of back fire or muffler 30 explosion.

It will be observed that I dispose of the switch construction and of the ordinary choking device.

I have adjusted the vapor port with reference to the carburetor admission so that the supply of mixture is set for all occasions; and it is provided that if the supply be at first a little richer than is needed for ordinary running so that the car may be 40 readily started, the operation of my regulating device will lean the mixture as desired.

In my device I avoid also the danger of drawing raw and vaporized gasoline 45 through the carburetor into the combustion chambers of the engine and forcing it into the crank case where it is mixed with the lubricating oil and destroys the qualities of the lubricant, causing burnt out bearings 50 and scorched cylinders, and making it impossible for the operator to determine the lubricating value of the oil in the crank case. I also, by the same device, provide for the introduction of such quantities of air as 55 to serve to prevent the combustion of the fluids in the engine, and at the same time cutting out the ignition circuits by the action of the pins carried by the whistles. At this time the whistles are in position to 60 operate as sirens. These will give a quick sharp alarm different from any other signal. It should be observed that sound waves can not be produced by other than siren constructions when operating by suction as 65 these waves pass into the body of the device

and are smothered with any other construction.

The connection between the piston-valve and its stem is such as to permit the piston-valve to be either moved gradually to secure 70 the control desired under ordinary circumstances, or to permit the piston-valve to be drawn back instantly permitting the flow of atmospheric air to create a motor-brake in the engine cylinder, cutting off the ignition device and bringing the whistles into communication with the air passage to the engine; so that, for example, if in running down hill the brakes should be disconnected, the motor-brake can be quickly applied and 75 at the same time the alarm sounded by the engine, turning under the momentum of the car. In such event if the driver should abandon the car and its momentum should carry it down hill, the alarm would be constantly sounding and the motor-brake applied.

It is a peculiar feature of my invention that the whistles are not operated or subject to operation independently of the operation of the engine. When the engine is inoperative they cannot be blown heedlessly or in a manner to annoy the public but can only be operated by an unauthorized attempt to start the engine. This is particularly important because the object of these whistles is to give notice to the police or others in preventing the theft of a car. The whistles have a distinctive, sharp, rolling sound due to their operation as siren whistles 100 which at once attracts attention and gives immediate and continuous notice of the event as long as there is any attempt to operate the motor, this peculiarity of sound being due to the well known variations in 105 the suction in such case.

In brief, my arrangement of a ported cylinder with a ported, hollow piston-valve is the most economical construction for a device of this character, and at the same 110 time, by the addition of my specific devices, the most effective. The parts are few, their operation is all in two directions, back and forth, and the whole device takes up a small space. Furthermore, I secure in a most 115 economical manner the control of the whistles by the same part which governs the vapor and air ports and by these movements I also control the ignition so that in reality from the control knob alone all the actions 120 or regulation are governed—the admission of vapor, the subsequent admission of atmospheric air, the formation of a motor brake or lock through the operation of large quantities of air in the engine, the setting of the 125 whistles and the cutting off of the ignition device.

It will be observed that in addition the structural arrangement of the air and vapor regulating parts I have combined with these 130

- parts the control of the ignition devices, have placed the alarm in communication with the air supply passage and have provided for controlling the ignition devices by 5 the operation of the whistles of the alarm. I refer to this again to emphasize the fact that I have brought the ignition control into this combination and into this small space so that all the regulating parts may 10 be brought close to the operator and so that any attempt to destroy the device can only result in rendering the engine inoperative. In the claims and generally throughout 15 the specification I have used the term "cylinder" as a general term covering receiving chamber; and I have used the term "vapor" to indicate, briefly, the humidified air which I supply to the cylinder. I claim.—
- 20 1. In an internal combustion engine, a device for controlling the engine comprising means for admitting vapor to (enrich) the combustion mixture, means for admitting air to lean the combustion mixture and for 25 admitting air to create a motor-brake, means for setting an alarm to be operated by the engine upon an attempt to start the engine, circuit-controlling devices moved by the alarm to be brought into operative position 30 when the alarm is disconnected and into inoperative position when the alarm is set, and a controlling means for governing the operation of all these features.
2. In an internal combustion engine, the 35 combination with an air supply passage leading to the engine, of an alarm adapted to be connected with the air supply passage so that it shall operate by the suction created in attempting to start the engine when it is 40 intended that the engine shall not operate.
3. In an internal combustion engine, the combination with an air supply passage leading to the engine, of siren whistles adapted to be brought into communication 45 with the air supply passage so that upon an attempt to start the engine when it is not intended that the engine shall operate air shall be drawn through the whistles to give an alarm.
- 50 4. In a device for regulating an internal combustion engine, the combination of a cylinder, means for admitting air to the cylinder, a siren whistle pivoted to the side of the cylinder, and means for bringing the 55 whistle into communication with the means for admitting air, so that upon an attempt to start the car a suction will be created through the whistle to give an alarm.
5. In an internal combustion engine, the 60 combination with means for feeding air to the intake manifold, of whistles carried by the air feeding means, means for controlling the ignition circuits, and means for bringing the parts into the desired operative positions.
6. In an internal combustion engine, the combination with an air passage leading to the engine, whistles in communication with the air passage and means for simultaneously bringing the whistles into operative 70 position to give an alarm and cutting out the ignition circuits.
7. In an internal combustion engine, the combination with means for supplying air to the engine, to create a motor-brake, an 75 alarm to operate upon an unauthorized attempt to start the engine and means for governing the application of the motor-brake and the alarm.
8. In an internal combustion engine, the 80 combination with whistles and ignition controlling devices, of means for supplying air to create a motor-brake in the engine and at the same time applying the whistles and the ignition controlling devices so that if the 85 engine be running away down hill the ignition circuits may be cut out and the alarm sounded while the motor-brake is in action.
9. In a device for regulating an internal combustion engine, the combination with a 90 ported cylinder communicating with the intake manifold to supply air or vapor, ignition controlling devices, a piston valve operating in the cylinder to control its ports and serving to govern the ignition control- 95
10. In a device for regulating an internal combustion engine, the combination with a cylinder to receive air and communicating with the intake manifold, alarms carried by 100 the cylinder, ignition controlling devices, and means operating in the cylinder to control the supply of air, to set the alarms and to govern the action of the ignition controlling devices.
11. In a device for regulating an internal combustion engine, the combination of a cylinder having a port for admitting vapor and a port for admitting atmospheric air, a piston-valve controlling the ports, whistles 110 carried by the cylinder, adapted to be brought into register with the atmospheric ports of the cylinder and controlled by the movements of the piston-valve.
12. In an internal combustion engine, the 115 combination with a ported cylinder, a piston-valve controlling the admission of air to the cylinder, whistles pivoted to the side of the cylinder, adapted to register with the cylinder ports, and controlled by the movements of the piston-valve.
13. In an internal combustion engine, the combination of a ported cylinder, a piston-valve controlling the ports of the cylinder, whistles pivoted to the side of the cylinder, 125 and registering with ports of the cylinder, a spring connecting the whistles, and cams attached to the whistles and adapted to engage the walls of the piston-valve through the ports of the cylinder.

14. In a device for regulating an internal combustion engine, the combination of a cylinder having ports for admitting vapor and air, a piston-valve controlling the ports, 5 whistles pivoted to the cylinder registering with the ports of the cylinder and controlled by the movement of the piston-valve, and devices carried by the whistles for controlling the ignition circuits.
- 10 15. In a device for regulating an internal combustion engine, the combination of a cylinder communicating with the engine, ports for admitting air to the cylinder, a valve controlling the air admission, and 15 siren whistles pivoted to the sides of the cylinder and communicating with the cylinder when the valve is moved to open the ports, so that upon an attempt to start the engine a suction will be created through the 20 whistles.
16. In a device for regulating an internal combustion engine, the combination of a ported cylinder communicating with the engine, a ported piston-valve, a pair of 25 whistles having projecting cams engaging the walls of the piston-valve through the cylinder ports, so that the whistles are permitted to be drawn against the cylinder and register with the ports when the valve is 30 moved in one direction, and forced away from the cylinder when the valve is moved in the opposite direction.
17. In a device for regulating an internal combustion engine, the combination with a 35 cylinder for receiving air, of means for controlling the admission of air to the cylinder to be delivered to the intake manifold of the engine, whistles pivoted to the sides of the cylinder, adapted to communicate with 40 the cylinder and operated by the means which control the air, and a device operated by the movements of the whistles for controlling the ignition device.
18. In a device for regulating an internal 45 combustion engine, the combination of a ported cylinder for receiving air to be sent to the intake manifold, a whistle pivoted to each side of the cylinder and adapted to register with the ports of the cylinder, and 50 means for swinging the whistle bodies away from the cylinder and means for bringing the whistle bodies close against the cylinder so that air may enter the cylinder through the whistles only by the effect of the suction 55 of the engine, thus operating as sirens and providing an alarm to indicate an attempt to start the engine.
19. In an internal combustion engine, the 60 combination of an insulating board carrying the connections with the battery and with the magneto, of a pair of whistles and means for swinging the whistles, one whistle bearing a pin to control the magneto connections, and the other whistle bearing a pin 65 to control the battery connections.
20. In a device for regulating an internal combustion engine, the combination with a cylinder having ports for admitting air, a piston-valve controlling the ports and adapted to be reciprocated in the cylinder, 70 whistles adapted to register with the ports and controlled by the piston-valve, and means for locking the piston-valve when the ports are open and the whistles are set for operation.
21. In a device for regulating an internal combustion engine, the combination with a cylinder ported to receive vapor and air, of a piston-valve controlling the ports, a stem connected to the piston and adapted to operate the piston longitudinally within the cylinder, and a lock to take over the stem when it is drawn out from the cylinder to hold the valve in the position it assumes when the engine is rendered inoperative. 75
22. In a device for regulating an internal combustion engine, the combination with a cylinder having air ports and communicating with the engine, a piston-valve controlling the ports, whistles adapted to be 80 brought into register with the ports, means for stopping the movement of the piston-valve when it reaches a position to provide for the admission of air in such quantities as to create a motor-brake in the engine, and 85 means for bringing the piston-valve to its final movement when the whistles register with the ports and are in operative position.
23. In a device for regulating an internal combustion engine, the combination with a 90 cylinder for receiving air to be supplied to the intake manifold of an engine, of a valve governing the admission of air, a stem for operating the valve, a head to determine the final movement of the valve, a stop on the 95 valve for preventing the complete opening movement of the valve, by contact with the head and a slot in the head to receive the stop when the completed movement is desired.
24. In a device for regulating an internal 100 combustion engine, the combination with a cylinder having ports for admitting fluids, of a hollow, ported piston-valve controlling the ports of the cylinder, a stem connected 105 with the hollow piston-valve and adapted to be either reciprocated or rotated to operate the valve quickly or by degrees.
25. In a device for regulating an internal 110 combustion engine, the combination of a cylinder for receiving vapor and air to be sent to the intake manifold, an alarm and a circuit breaking device, with a single means for governing the admission of vapor, the admission of air, the operation of the 115 alarm and the breaking of the circuit.
26. In a device for regulating an internal 120 combustion engine, the combination with a cylinder for receiving vapor and air to be supplied to the engine, of a valve for gov- 125

erning the supply, and a hand-operated, rotary stem for operating the valve, the stem having a threaded portion and means for engaging the threaded portion so that upon 5 each measured turn of the stem there shall be an audible sound indicating the turn.

27. In an internal combustion engine, the combination with a ported cylinder, of a valve for governing the ports, a stem attached to the valve, a guide through which 10 the steam passes, a threaded section on the stem, an anti-friction ball traveling in the groove of the thread, and means for applying a regulated pressure to the ball so that 15 the threaded stem may be either rotated or

reciprocated with the proper degree of action in engines of different vacuum.

28. In an internal combustion engine, the combination of a ported cylinder, a valve for controlling the ports, a rotary stem connected to the valve, a threaded portion on the stem having notches or depressions, an anti-friction ball held against longitudinal movement turning in the groove of the thread and riding over the notches or depressions and thereby giving an audible sound in each operation of the stem. 20 25

In testimony whereof I affix my signature.

FRANCIS J. WALLACE.
